MOTORIZED PACK CARRIER
Antonio Fonda, 925 8th Ave., Tracy, Quebec, Canada
Filed Jan. 28, 1965, Ser. No. 428,740
8 Claims. (Cl. 115—1)

This invention relates to a novel and useful motorized pack carrier and more specifically to an apparatus including an elongated and generally horizontally disposed load supporting frame from one end of which a buoyant drum-type powered drive wheel is journaled. The pack carrier includes elongated and generally horizontally disposed handle means and the handle means and the elongated frame include means reversibly securing one end portion of the handle means to the frame with the other end portion of said handle means projecting from opposite ends of said frame in alternate positions of attachment of said handle means to said frame.

The motor means by which the drum-type drive wheel is powered is supported from the end of the frame of the pack carrier remote from the drive wheel. By this construction the weight of the motor means driving the drum-type drive wheel and any load supported from the elongated main frame of the pack carrier may be disposed on the same or other side of the axis of rotation of the drive wheel, relative to the handle means. By positioning the handle means and the motor means as well as any load supported by the frame of the pack carrier on the same side of the axis of rotation of the drive wheel a person supporting the free end of the handle means will have to apply an upward supporting thrust of the free end of the handle means inasmuch as a portion of the weight of the motorized pack carrier minus its drive wheel, the motor means for driving the drive wheel and any load supported from the frame of the pack carrier will be transmitted to the free end of the handle means. On the other hand, should the handle means be reversed so that the free end thereof projects from the other end of the frame of the pack carrier, the weight of the handle means will be overbalanced by the weight of the drive motor and any load supported from the main frame of the pack carrier and therefore a person operating the pack carrier will have to apply a downward thrust on the free end of the handle means.

It is believed that it will be readily apparent from the description of the pack carrier set forth hereinafter that there are numerous advantages to providing such a motorized pack carrier with reversible handle means in that the reversibility of the handle means enables a portion of the total weight of the pack carrier to be supported from the drive wheel of the pack carrier to be varied.

The main object of this invention is to provide a motorized pack carrier including means by which a heavy load may be readily supported and moved from one location to another.

Still another object of this invention is to provide a motorized pack carrier which may be utilized to effect a horizontal driving thrust on a load supported from the medium from which the pack carrier is supported.

Yet another object of this invention is to provide a motorized pack carrier including a buoyant drive wheel including a plurality of circumferentially spaced generally radially outwardly projecting and longitudinally extending paddle wheel drive lugs in order that the motorized pack carrier may be afforded maximum traction when supported from soft ground or snow and also be utilized as a motive force when the pack carrier is supported on a body of water with the lower portion of the drive wheel disposed in the water.

An ancillary object of this invention is to provide the drive wheel of the motorized pack carrier with circum-

ferentially extending ground-engaging strap means removably secured by the drive wheel bridging the spacing between adjacent paddle wheel drive lugs whereby the pack carrier may be utilized on a smooth supporting surface such as a road without the paddle wheel-drive lugs causing excessive vibration of the pack carrier.

A final object of this invention to be specifically enumerated herein is to provide a motorized pack carrier in accordance with the preceding objects which will conform to conventional forms of manufacture, be of simple construction and easy to use so as to provide a device that will be economically feasible, long lasting and relatively troublefree in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a top plan view of the motorized pack carrier shown with portions of the elongated and horizontally disposed handle means broken away;

FIGURE 2 is a side elevational view of the assembly illustrated in FIGURE 1 with parts of the motorized pack carrier being broken away and shown in vertical section;

FIGURE 3 is a transverse vertical sectional view taken substantially upon the plane indicated by the section line 3—3 of FIGURE 1;

FIGURE 4 is a fragmentary enlarged longitudinal vertical sectional view taken substantially upon the plane indicated by the section line 4—4 of FIGURE 1;

FIGURE 5 is a fragmentary front elevational view of the pack carrier as seen from the left side of FIGURE 4 and with portions of the pack carrier broken away and shown in transverse vertical section;

FIGURE 6 is a fragmentary exploded perspective view of the releasable latch means by which the hood of the pack carrier may be secured in the closed position;

FIGURE 7 is a fragmentary enlarged transverse vertical sectional view taken substantially upon the plane indicated by the section line 7—7 of FIGURE 4;

FIGURE 8 is a side elevational view of the pack carrier being used to transport a load on land;

FIGURE 9 is a fragmentary enlarged vertical sectional view illustrating the manner in which tread rings may be secured to the drum;

FIGURE 10 is a side elevational view of the pack carrier being utilized to support and push a snow plow;

FIGURE 11 is a side elevational view illustrating the pack carrier being used to propel a boat; and

FIGURE 12 is a side elevational view similar to FIGURE 8 but with the handle means of the pack carrier reversed in position.

Referring now more specifically to the drawings the numeral 10 generally designates the pack carrier of the instant invention. The pack carrier 10 includes a main frame generally referred to by the reference numeral 12 comprising a pair of rigidly interconnected longitudinal frame members 14 and 16. The rear ends of the longitudinal frame members 14 and 16 have a pair of journal blocks 18 supported therefrom and an axle member 20 is rotatably journaled from the journal blocks 18 and has a drum-type drive wheel 22 mounted thereon. The axle 20 also has a drive sprocket 24 mounted thereon and a plurality of paddle wheel drive lugs 26 are spaced circumferentially about the drive wheel 22 and project generally radially outwardly therefrom.

A source of motive power in the form of motor means 28 is supported from the end of the frame 12 remote from the drive wheel 22 in any convenient manner and

is generally designated by the reference numeral 28. The motor means 28 includes a rotatable output shaft 30 on which a small diameter sprocket wheel 32 is secured. The sprocket wheels 24 and 32 are aligned and the sprocket wheel 32 is drivingly connected to the sprocket wheel 24 by means of an endless chain 34.

A hood assembly generally referred to by the reference numeral 36 including a top wall 38 and a pair of longitudinally extending and depending opposite side walls 40 and 42 is provided and partially embraces the drive wheel 22 and encloses the motor means 28. The hood 36 includes rigidifying generally U-shaped brace means 44 and 46. The brace means 44 and 46 are each generally inverted U-shaped in configuration and secured to the top wall 38 as well as the opposite side walls 40 and 42. In addition, the lower ends of the legs 48 and 50 of the brace means 44 are pivotally secured to the main frame 12 in any convenient manner such as by pivot fasteners 52 and 54.

The motor means 28 includes an internal combustion engine 56 and a speed reducing and reversing transmission 58. The internal combustion engine 56 includes a power output shaft 60 which is coupled to the power input shaft 62 of the transmission 58 by means of a releasable clutch 64 and the transmission 58 includes a power output shaft comprising the shaft 30. The transmission 58 may be utilized to reverse the direction in which the drive wheel 22 is rotated by the motor means 28.

The hood 36 substantially completely encloses the motor means 28 including the internal combustion engine 56 and the transmission 58 and frame 12 includes a belly pan portion 65 extending beneath the internal combustion engine 28.

A pair of elongated handles 66 and 68 are provided and are releasably secured to the side walls 40 and 42 by means of pairs of releasable clamp rings 70 and 72 or the like. As can be seen by a comparison of FIGURES 8 and 12 the handle means comprising the handles 66 and 68 may be readily reversed. The handle 68 includes a control assembly 76 including ignition and throttle controls 78 and 80 with the internal combustion engine 56 and the handle 66 includes a gear shifting control and a clutch control 82 and 84 for control of the operation of the transmission 58 and the clutch 64.

The main frame 12 includes a rear transverse member 90 and a pair of latching mechanisms generally referred to by the reference numeral 92 are supported from the side walls 40 and 42. Each of the latching mechanisms 92 includes a mounting plate 94 suitably apertured as at 96 and secured to the corresponding side wall by means of fasteners 98 secured through the apertures 96. The mounting plates 94 each also include a stub axle portion 100 and an actuating disk 102 which is suitably apertured as at 104 and includes an eccentrically disposed crank pin 106 is journaled on each stub axle 100. Each of the actuating disks 102 includes an operating handle 108 in the form of an angle member and has one end of a latching arm assembly generally referred to by the reference numeral 110 pivotally secured to the corresponding eccentric pin 106. Each latching arm 110 is apertured as at 112 to rotatably receive the corresponding eccentric pin 106 and defines a first section 114 in which the corresponding aperture 112 is formed and which includes an apertured right angulated end portion 116 remote from the aperture 112. A second section 118 has a threaded shank portion 120 extending longitudinally of one end and the shank portion 120 of each latching arm is secured through the apertured laterally directed end portion 116 by means of suitable nuts 122 threadedly engaged on the shank portion. The end of the section 118 remote from the threaded shank portion 120 is hooked as at 124 and is engaged under the corresponding end of the transverse member 90. In addition, each of the side walls 40 and 42 has a lock-

ing lever 126 pivotally secured thereto as at 128. In securing the hood 36 in its closed position the disks 102 are first rotated in a direction to position the pins 106 closer to the transverse brace member 90. Then, the hooked end portions 124 engaged under the transverse brace member 90 and the disks 102 are rotated so as to move the pins 106 away from the transverse brace member 90. After the latching arms 110 have been tensioned, the levers 126 may be swung into position abutting the free ends of the corresponding handles 108 to retain the disks 102 in their positions of adjustment securing the hood 36 in its closed position.

With attention now invited to FIGURES 9 and 12 of the drawings it may be seen that the drive lugs or paddles 26 may be adapted for smoother operation on a level supporting surface 130 by the securement of a pair of tread rings 132 which are split and joined together as at 134. Each of the tread rings 132 includes a resilient outer tread surface 136 and each of the rings 132 defines a simple ring clamp which may be secured about the drum by means of fasteners 138 secured through the inturned flanges 140 formed on the abutting ends of each ring 132.

With attention now directed to FIGURES 8 and 12 of the drawings it may be seen that the handles 66 and 68 may be reversed so as to selectively position the load 134 and the center of gravity of the main frame 12 including the internal combustion engine 28 between the free end of the handles 66 and 68 and the axis of rotation 30 of the ground engaging wheel or drum 22 as viewed in FIGURE 12 of the drawings or on the side of the axis of rotation of the drum 22 remote from the free ends of the handles 66 and 68 as shown in FIGURE 8 of the drawings. The operator 136 of the pack carrier 10 in FIGURE 12 of the drawings has to exert an upward force on the free ends of the handles 66 and 68 to maintain the pack carrier 10 in a substantially horizontally disposed position and therefore a portion of the total weight of the pack carrier 10 is supported by the operator 136 and removed from the point of contact 140 of the drum 20 with the supporting surface 130. However, the operator 136 in FIGURE 8 of the drawings must maintain a downward force on the free ends of the handles 66 and 68 to counterbalance the center of gravity of the load 134 and the frame 12 and the internal combustion engine 28 of the pack carrier 10 and therefore an additional downward thrust is applied by the drum or wheel 22 at the point of contact 142 with the supporting surface 130 in FIGURE 8 of the drawings. Thus, reversing the handles 66 and 68 from the positions illustrated in FIGURE 12 of the drawings to the positions illustrated in FIGURE 8 of the drawings affords greater traction for the drive wheel or drum 22 of the pack carrier 10.

In FIGURE 10 of the drawings a scraper blade assembly generally referred to by the reference numeral 144 is shown secured to the front of the pack carrier 10 and the handles 66 and 68 are positioned to extend rearwardly of the drive wheel or drum 22 thereby enabling the weight of the frame 12 in the internal combustion engine 28 to apply a downward thrust on the scraper blade assembly 144.

In FIGURE 11 of the drawings a pair of float assemblies 146 have been secured to the opposite sides of the frame 12 of the pack carrier 10 and the free ends of the handles 66 and 68 are secured to the bow portion 148 of a boat hull 150, a portion of the weight of the pack carrier 10 therefore being supported by the boat hull 150 and enabling the floats 146 to maintain the pack carrier 10 at a higher elevation relative to the water 152 than would be possible if the handles 66 and 68 were positioned as illustrated in FIGURE 8 of the drawings.

The foregoing is considered as illustrative only of the principles of the invention. Further, since numerous modifications and changes will readily occur to those skilled in the art, it is not desired to limit the invention to

the exact construction and operation shown and described, and accordingly all suitable modifications and equivalents may be resorted to, falling within the scope of the invention as claimed.

What is claimed as new is as follows:

1. A motorized pack carrier comprising a main frame defining a pair of opposite side and spaced apart support points, a wide and generally cylindrical buoyant drive wheel journaled from said support points for rotation about an axis extending between said points, motor means supported from said frame and drivingly connected to said drive wheel, said main frame being elongated and generally horizontally disposed, said support points being disposed on one end portion of said frame and the center of gravity of said motor means being disposed on the side of a vertical plane extending transversely through said frame equidistant from the opposite ends of said frame remote from said axis of rotation of said drive wheel, and elongated and generally horizontally disposed handle means, said handle means and said main frame including means reversibly securing one end portion of said handle means to said frame with the other end portion of said handle means projecting from opposite ends of said frame in its alternate positions of attachment to said frame, said other end portion of said handle means including control means operative to control the operation of said motor means, said buoyant wheel displacing a quantity of water over that quantity of water which has the same weight as said carrier.

2. The combination of claim 1 wherein said drive wheel includes a plurality of circumferentially spaced, generally radially outwardly projecting and longitudinally extending paddle wheel drive lugs.

3. The combination of claim 2 including circumferentially extending ground engaging strap means secured about said drive wheel and bridging the spacing between adjacent drive lugs, said strap means comprising a plurality of straps spaced axially along said drive wheel.

4. The combination of claim 1 wherein said one end portion of said frame defines a downwardly opening frame portion generally inverted U-shaped in transverse cross-section and defining a pair of upright sides interconnected by means of an upper generally horizontal bight portion, said downwardly opening frame portion at least partially embracing the upper portion of said drive wheel.

5. The combination of claim 1 wherein said main frame defines a downwardly opening frame portion at least partially embracing said drive wheel and enclosing said motor means.

6. A motorized pack-carrier comprising a main frame defining a pair of opposite side and spaced-apart support points, a wide and generally cylindrical drive wheel journaled from said support points for rotation about an axis extending between said points, motor means supported from said frame and being drivingly connected to said drive wheel, said main frame being elongated and generally horizontally disposed, said support points being disposed on one end portion of said frame and the center of gravity of said motor means being on the side of a vertical plane extending transversely through said frame equidistant from the opposite ends of said frame remote from said axis of rotation of said drive wheel, elongated generally horizontally disposed handle means, said handle

means and said frame including coacting means reversibly securing one end portion of said handle means to said frame with the other end portion of said handle means projecting from opposite ends of said frame in its alternate positions of attachment to said frame, said main frame means including a generally horizontal and inverted U-shaped hood extending longitudinally thereof and including a pair of depending side walls interconnected by means of a transversely extending top wall, means pivotally securing one end of said hood to said frame for rotation about an axis extending between the lower portions of the ends of said side walls adjacent the first mentioned axis, said hood and said main frame including means releasably securing said hood in a generally horizontal position relative to said frame.

7. The combination of claim 6 wherein said hood at least partially embraces the upper portion of said drive wheel and encloses said motor means.

8. A motorized pack carrier comprising a main frame defining a pair of opposite side and spaced apart support points, a wide and generally cylindrical drive wheel journaled from said support points for rotation about an axis extending between said points, motor means supported from said frame and drivingly connected to said drive wheel, said main frame being elongated and generally horizontally disposed, said support points being disposed on one end portion of said frame and the center of gravity of said motor means being disposed on the side of a vertical plane extending transversely through said frame equidistant from the opposite ends of said frame remote from said axis of rotation of said drive wheel, and elongated and generally horizontally disposed handle means, said handle means and said main frame including coacting means reversibly securing one end portion of said handle means to said frame with the other end portion of said handle means projecting from opposite ends of said frame in its alternate positions of attachment to said frame, said main frame means including a generally horizontal and inverted U-shaped hood extending longitudinally thereof and including a pair of depending side walls interconnected by means of a transversely extending top wall, means pivotally securing one end of said hood to said frame for rotation about an axis extending between the lower portions of the ends of said side walls adjacent the first-mentioned axis, said hood and said main frame including means releasably securing said hood in a generally horizontal position relative to said frame, said handle means being supported from said hood.
